Primary Examiner — Ricky Pham

(57) **CLAIM**

The ornamental design for a kitchen machine, as shown and described.

DESCRIPTION

FIG. 1 is a perspective view of a kitchen machine according to an embodiment;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view shown in a state of use.

The short dash broken lines in the drawings depict portions of the kitchen machine that form no part of the claimed design.

The diagonal shaded lines in the figures show a display surface.

1 Claim, 9 Drawing Sheets
